DESIGN FOR A FISH LURE

James W. Dehnert, Landing, N. J.

Application September 10, 1937, Serial No. 71,544

Term of patent 14 years

To all whom it may concern:

Be it known that I, James W. Dehnert, a citizen of the United States, residing in Landing, in the county of Morris and State of New Jersey, have invented a new, original, and ornamental Design for a Fish Lure, of which the following is a specification, reference being had to the accompanying drawing, forming part thereof.

In the drawing, Figure 1 is a side view. Figure 2 is a top view and Figure 3 is a front view of a fish lure, showing my new design.

I claim:

The ornamental design for a fish lure, as shown.

JAMES W. DEHNERT.
